UNITED STATES PATENT OFFICE.

WILLIAM B. TURNER, OF NEW YORK, N. Y., ASSIGNOR OF ONE-HALF TO
CORNELIUS BEARD, OF SAME PLACE.

AUTOMATIC CAR-BRAKE.

SPECIFICATION forming part of Letters Patent No 278,835, dated June 5, 1883.

Application filed December 15, 1882. (No model.)

To all whom it may concern:

Be it known that I, WILLIAM B. TURNER, a citizen of the United States of North America, and a resident of the city, county, and State of New York, have invented a new and useful Improvement in Momentum Car-Brakes, of which the following is a specification.

This invention relates to an improvement in that class of car-brakes which are made operative by the action of the draw-bar, and having their connections between the brake-levers and draw-bars constructed to be disengaged at each change in direction.

The invention consists of a car-brake adapted to be automatically adjusted from an operative position in one direction to an operative position in the opposite direction by the rotation of the car-axle operating through an eccentric or toothed collar and other suitable mechanism, such adjustment being effected at each change in the direction of the wheel rotation, no matter to which end of the car the engine is attached or whether pushed or pulled.

Reference is to be had to the accompanying drawings, forming part of this specification, in which similar letters of reference indicate corresponding parts in all the figures.

Figure 1 is a partly-sectional side elevation of a portion of a car-frame with my improved brake applied. Fig. 2 is an enlarged side elevation of certain details of my brake. Fig. 3 is a plan view of a car-frame with parts broken away to exhibit other parts, showing portions of my brake mechanism in position. Fig. 4 is an enlarged edge elevation of the swinging frame, its attachments, and supports. Fig. 5 is an enlarged side elevation of the same. Fig. 6 is an enlarged side elevation of upper portion of the operating-lever and its attachments or connections. Fig. 7 is an enlarged plan of the operating-lever, sleeve, and cam-rod. Fig. 8 is an enlarged plan of one end of the pitman that is adapted to clasp the head of the operating-lever. Fig. 9 is an enlarged partly-sectional elevation, showing a portion of the operating-lever, the clip in which it is fulcrumed, and the clip supports or guides. Fig. 10 is an enlarged plan view of the clips and their attachments. Fig. 11 is an enlarged

front elevation of the axle collar or pulley in 50 position. Fig. 12 is an enlarged longitudinal sectional elevation of the same. Fig. 13 is an enlarged cross-section of the same. Fig. 14 shows a modification of a portion of my improved device. Fig. 15 shows another modification of a portion of the same. Fig. 16 represents an enlarged partly-sectional plan view of draw-head, draft-timbers, slides, follower-plates, and draw-head spring in their normal position. Fig. 17 is a partly-sectional side elevation of same with the draw-head compressed. Fig. 18 is a partly-sectional elevation of the same with the draw-head extended.

In the drawings, A represents a car-frame; B B', the front and rear axles, and C C' the 65 front and rear wheels, respectively, of a truck.

On the shank of the draw-bar D, held apart by spring D³ surrounding said shank, are two follower-plates, D' D'', respectively, that are normally held between grooved slides D⁴, which are 70 secured opposite and parallel to each other on the draft-timbers D⁵, as shown in Figs. 16, 17, and 18, the former or front plate being adapted to be moved rearward by the compression of the draw-bar and forward by the action of the 75 spring D³, and the latter or rear plate being movable rearward by the spring action and forward by the extension of the draw-bar, the normal position of said draw-bar, follower-plates, and spring being shown in Fig. 16. 80

Held loosely upon the draw-bar, between the plate D' and the forward end of the spring D³, is a hanger, E, to the lower end of which is hinged or pivoted the forward end of a pitman, E, extending horizontally rearward through a 85 swinging frame, F, and having its forked end adapted to clasp the head of the operating-lever I.

From the lower end of the plate D² a link, F', extends rearward above the pitman E, its 90 slotted end having engaged in it the upper pin, a, of the swinging frame F, so that the movements and position of the latter shall be controlled by the compression or extensions of the draw-bar partly through the medium of said 95 link F'.

Secured opposite each other upon the car-timbers are hanging plates G G', whose free

ends are held opposite and apart from each other by rods *b c*, and between these plates *G G* is suspended the swinging frame *F*, which is supported by the pitman *E*, that passes between its pins *f g*. Said frame *F* consists of two plates, *d d*, preferably of iron, held apart and opposite each other by bars or pins *a f g*, between the latter two of which the pitman *E* passes, as before said, and from each plate *d*, 10 from about the center of the rear edge thereof, there projects laterally stops *h*, that are designed to always rest against the rear edge of the plates *G G*.

On the car-timbers, below the plates *G G*, 15 are secured two depending opposite plates, *H H'*, of wood or metal, on the former of which is pivoted by a pin, *h'*, a rocking lever, *K*, having pivoted upon it two opposite and forward-projecting dogs, *K' K''*, respectively, each provided with an inward-projecting nose, *i*. A spring, *K''*, stretched between these dogs *K' K''* holds them toward each other, and so that they may, when desirable in the operation of the brake, be brought in contact with the tooth or eccentric *L'* of a collar, *L''*, that is rigidly secured on the front axle, *B*, said dogs *K' K''* being held in position when in operation by contact of their free extremities with pins *k*, that project laterally from the plate *H*. The tooth *L'* is properly termed an "eccentric," because it, in revolving, makes an eccentric or crank motion, or operates to produce alternate or reciprocating motion.

To the upper end of the rocking lever *K* is 35 pivoted a rearwardly-extending lever, *M*, having a cam-tooth, *l*, the rear end of which cam-lever *M* is supported on a pin, *m*, that projects laterally from the operating-lever *I*, and this rear end of the lever *M* is connected by a link, 40 *l'*, with a sleeve, *I'*, that fits loosely about the head of the operating-lever *I* and affords a support for the rear end of the pitman *E*.

About the axle *B* is also rigidly fixed a motor friction-pulley, *N*, that is preferably constructed of two semi-cylindrical castings, *n n*, banded together at their ends with ring-clamps *n' n'*, that may at any time be readily removed to permit the renewal of said castings *n n*, or either of them.

50 Journaled in an oblong bearing (not shown) of the plate *H'*, and supported also in a slot (not shown) of a parallel supporting bar or plate, *H''*, is a shaft, *O'*, on which is rigidly secured a friction-pulley, *O*, that is designed, 55 when required, to be forced in connection with the axle-pulley *N*; and extending from said shaft *O'* to the operating-lever *I*, with its ring or eyed end embracing said shaft and its other end pivoted to the lower end of said operating-lever, as shown, is a pitman, *P*, that serves to 60 transmit the motion of the said lever *I* when the brakes are to be applied.

The plates *H H' H''* constitute the frame, which is attached to the car-truck and supports a portion of the brake mechanism. A spiral spring, *s*, extending from a truck-tim-

ber forward to the lower end of the lever *I*, serves to withdraw the operating-pulley *O* from contact with the motor-pulley *N* when the brakes are released. The operating-lever 70 *I* is pivoted in a jaw or clip, *Q*, that is connected with a rearward clip, *Q'*, by a spiral spring, *Q''*, and this clip *Q'* is in turn pivoted to the lower end of a crank-lever, *R*, that is fulcrumed on the plate *H'*, and has its free end 75 curved upward to be in contact with the under face of the bolster *S*. Hence it will be seen that the spring *Q''* may operate effectively to force the lower end of the lever *I* forward for the more positive application of the friction-pulley *O* to the axle-pulley *N*, and also that the weight of the car operating on the free end of the crank-lever *R* will emphasize such application. Another special advantage of the spring-fulcrum of the operating-lever is that 80 it prevents injury or distortion of the parts by yielding when the draw-bar is too violently compressed, and by yielding it prevents more pressure on the friction-pulley against the axle-pulley and consequent application of unnecessary braking force or power.

The clips *Q Q'* are supported in position on and between guides *Q''*, that are themselves secured to or formed on the plates *H' H''*, as shown in Fig. 9.

95 The brake-beams *T* and shoes *T'* are of the ordinary kind, as are the brake-levers *U*, the brake connecting-rod *U'*, and brake-chain *V*, the latter having one end connected to the lever *U* and the other to the friction-pulley 100 shaft *O'*, the bight of said chain being passed over a supporting-sheave, *W*, that is supported on a shaft projecting from the plate *H'*.

As shown in Fig. 1, the brake mechanism is 105 in the disengaged position it would assume if the car were being pulled in the direction of the arrow and the draw-head extended. If, now, the engineer wishes to stop the train, he

would slow the engine with the effect of compressing the draw-bar *D*. This compression 110 of the draw-bar *D* forces the pitman *E*, and consequently the head of the operating-lever *I*, rearward, as indicated in dotted lines, Fig. 17, whereby, through the medium of the pitman *P*, the friction-pulley *O* is brought into 115 contact with the axle-pulley *N*, and the chain *V* at once begins to be wound up on the shaft *O'* with the effect of applying the brakes. The train being stopped, if now the engine is moved forward, the consequent extension of the draw-bar 120 operates to disengage the brakes by withdrawing the pitman *E* from the top of the lever *I*, as indicated in Fig. 18, thereby permitting the spring *s* to pull the bottom of the said lever *I* rearward, and causing thereby the pitman *P* 125 to remove the pulley *O* from contact with the axle-pulley *N*, which pulley *O* is then free to revolve in the direction opposite to that in which it was wound up and disengage the brakes. Then, if the car is backed, the car-axle revolves 130 backward, and as soon as the eccentric *L'* comes in contact with the nose *I* of the dog *K'* it

forces said dog rearward, with the effect of pushing the head of the rocking lever K rearward, as shown in Fig. 2, and by this movement of lever K the cam-rod M is pushed rearward, so that the tooth or 'cam' l of the latter is forced up over and beyond the pin or stop m of the operating-lever I. In its rise over said stop m the lever M, operating through the link l' , elevates the sleeve I', and thereby the end l of the pitman E, above the top of the lever I, as shown in full lines, Fig. 17. The pitman E being thus disengaged from the lever I, the compression of the draw-bar ceases to operate for applying the brakes, and the spring s then 15 operates to withdraw the operating friction-pulley O from contact with the motor or axle friction-pulley N, thereby effecting a disengagement of the brake mechanism. The pitman E, when thus raised, lifts with it the 20 swinging frame F, the lower end of which consequently swings forward, as indicated in dotted lines, Fig. 5, so that when the car is pulled forward again the extension of the draw-bar causes the forked end of the pitman E to be brought in front of the head of the lever I, as indicated in Fig. 18, and said frame F then drops down and rests upon the rod c at the bottom of said plates G G; and said frame F then becomes the support 25 of said pitman E, and holds it up so that it will not engage with the top of the lever I. This arrangement permits the engineer to back the train and then reduce the speed of the engine, which will allow the cars to run away from each other, and thereby pull out the draw-bar, so that the engineer can back up again without causing the application of the brake. It will be seen that if, when the cars were pushed rearward and separated from each 30 other as far as their draw-heads and couplings would admit without compression of the spring D', the pitman E were permitted to fall and engage with the top of the lever I, the pushing in of the draw-head and further backing up of the train would apply the brakes; hence, as this would be just the reverse of what would be desired, the pitman E is held disengaged from the lever I by the frame F, as just stated. Now, in order to bring the pitman E into 35 the position required for an application of the brakes, the draw-bar D must be pulled out sufficiently to compress the spring D', and at the same time the follower-plate D', to which the link F' is connected, is drawn forward, 40 whereby the top of the swinging frame F is drawn forward and caused to take its normal position, as shown in full lines, Fig. 5, whereby the pitman E is permitted to re-engage with the lever I. 45

It will be seen that the dogs K' K², lever K, and rod M, constitute, with the link and sleeve l' I', the means for the disengagement of the pitman E from the lever I, whereby is caused, 50 through suitable mechanism, as hereinbefore set forth, the disengagement of the brakes, and when pitman E and lever I are engaged the compression of the draw-bar, through suitable

mechanism, as described, causes the contact of the friction-pulleys N O, and, if during said contact the wheels are revolving, causes the application of the brakes, for it is obvious that the eccentric L' cannot engage with the nose of the dog K² when the parts are in position shown in Fig. 1 and the car is being pulled in the direction of its arrow; and now, if the car be stopped 55 and backed, the eccentric L' will engage with the nose of the dog K² and through its medium will cause the rocking lever K to assume position shown in Fig. 2, whereby, through the medium of the cam-rod M and its attachments, 60 the pitman E is disengaged from the lever I, thereby effecting a disengagement of the brakes. Thus it will be seen that the brake mechanism, although operated upon for braking always, with one exception, by the compression of the draw-bar, is not operated upon for braking unless the mechanism is automatically adjusted in correspondence with the direction of wheel rotation. The exception referred to is when the engine is slowed so as to 65 allow the cars to separate and then backed up again and the draw-bar compressed thereby, in which case the swinging frame F, being the support of the pitman E, does not allow the latter to engage with the lever I. In this particular lies the great difference between the motion-governed and the direction-governed 70 75 80 85 90 95 100 105 110 115 120 125 130 135

Motion or centrifugal brakes require no adjustment, as they are always ready to operate whenever their proper speed of revolution is reached, whereas direction-brakes must be adjusted to correspond with the direction of motion, and if this is done automatically, as in this case, it must be done at each change in direction.

In Fig. 14 is shown a modification of my brake mechanism, wherein an eccentric, X, is secured on the car-axle B and has a strap, q, inclosing it, from which extends a slotted rod, q', through the slot of which the pivot of the rocking lever K passes to support it. This rod q is provided at each side with teeth r r', and as the axle B revolves these teeth r r' operate in the same manner on the dogs K' K² as does the eccentric L', as above explained.

In Fig. 15 is shown another modification of my brake, wherein a pulley, Y, provided with a crank-pin, t, operates as an eccentric when brought in contact with a collar, Z, fixed on the axle B by means of teeth r r' on its rod q', as set forth in relation to the device shown in Fig. 14. It will be further observed that but one brake or device of this construction and method of operating is required to each car, because it automatically adjusts itself for operating in whichever direction the car is moving, whether the engine be attached to the one or other end thereof. In this respect it is especially distinguishable from other rotary brakes. I do not herein broadly claim the modification of my brake, because I design making them subjects of future applications. I do not broadly claim frictional devices

whereby the application of the brakes is caused by the rotation of the car-axle. Nor do I broadly claim devices whereby the momentum of the train or car is made operative to stop the same by or through the compression of the draw-bar, for devices of this character are not new. Nor do I claim, broadly, mechanism operated by the rotation of the car-axle for changing the position of the connection between the draw-bar and the brake-lever.

Any novel feature shown herein and not claimed I reserve the right to make the subject of a separate application.

Having thus described my invention, what I claim as new, and desire to secure by Letters Patent, is—

1. In a momentum car-brake, operative when the car is running with either end forward, by the inward movement of the draw-bar, the combination, with such draw-bar, of a friction device set in motion by the axle for operating the brake, and a tripping device operated at each change of direction of wheel rotation, substantially as described.
2. In a momentum car-brake wherein the brakes are applied through suitable mechanism by the combined compression of the draw-bar and rotation of the car-axle, the combination, with the car-axle, of a collar having a peripheral tooth fixed thereon, a lever provided with attached pivoted tooth-engaging dogs, and a pivoted cam-rod provided with means, substantially as described, for adjusting the position of the connection between the operating-lever and draw-bar, as set forth.
3. In a momentum car-brake provided with a draw-bar pitman and operating-lever, the combination, with said pitman and lever, of a swinging frame, substantially as described, for holding said pitman in a disengaged position after being supported and raised by the said pitman, as set forth.
4. In a car-brake, as a means for automatically disengaging the draw-bar pitman from the operating-lever, the combination, with said lever and pitman, of a sleeve constructed to be moved upward for disengaging the lever, substantially as described.
5. In a car-brake, as a means for automatically reconnecting the draw-bar pitman with the operating-lever for the purpose of adjusting the brake mechanism for application, the combination, with the draw-bar and its pitman and the swinging frame F, of a rear follower-plate actuated in one direction by the spring and in the other by said draw-bar and a link connecting the same with the said swinging frame, substantially as herein shown and described, and for the purpose set forth.
6. In a car-brake, the combination, with the draw-bar and the hanger E', loosely secured thereon, of the pitman E, constructed to move with said hanger, and arranged to act on the operating-lever and to be automatically disengaged therefrom, substantially as herein shown and described.
7. In a momentum car-brake, the combina-

tion, with the draw-bar and operating-lever, of a draw-bar pitman constructed with forked rear ends, and mechanism, substantially as described, for disengaging the pitman and lever, as set forth.

8. In a car-brake, operative with either end of the car forward, the combination, with the car-axle B, of a collar, L², having a peripheral tooth, L', and means, substantially as described, for operating the tripping device at each change of wheel rotation and only at such change, substantially as described.

9. In a momentum car-brake, the combination, with the car-axle B, provided with rigidly-fixed collar, L², having tooth or eccentric L' of the rocking lever K, pivoted lever-dogs K' K², and spring K³, substantially as herein shown and described, and for the purpose set forth.

10. In a momentum car-brake, the combination, with the car-axle B, provided with rigidly-fixed eccentrically-toothed collar L², of the rocking lever K, lever-dogs K' K², spring K³, and rod M, all arranged and operating substantially as herein shown and described.

11. In a momentum car-brake, the combination, with the operating-lever I, of the sleeve I' and means for raising said sleeve on said lever, substantially as herein shown and described.

12. In a momentum car-brake, the combination, with the operating-lever I, adjustable shaft O', and friction-pulley O, fixed thereon, of the pitman P, substantially as and for the purpose described.

13. The combination, with the car-axle pulley N, operating-lever I, adjustable shaft O', friction-pulley O, and pitman P, all arranged substantially as herein set forth, of the spring s, whereby the said pulley O may be withdrawn from contact with the pulley N, as described.

14. In a momentum car-brake, the combination, with the operating-lever I, draw-bar D, and movable hanger E', of the draw-bar pitman E, substantially as herein shown and described.

15. In a momentum car-brake, the combination, with the operating-lever I, draw-bar D, movable hanger E', and pitman E, of means for detaching said pitman from said lever, substantially as herein shown and described.

16. In a momentum car-brake, the combination, with the draw-bar pitman E, of the swinging frame F, substantially as herein shown and described, whereby said pitman is supported when the brakes are disengaged, as set forth.

17. In a momentum car-brake, the combination, with the swinging frame F, draw-bar D, follower-plate D², and spring D³, of the link F, substantially as herein shown and described, whereby the said swinging frame or pitman support is returned to its normal position, as set forth.

18. In a car-brake, operative with either end of the car forward, the combination, with a car-axle and the brake, of a disengaging de-

vice provided with a toothed collar arranged to revolve with the axle, constructed to cause said device to disengage the connection between the draw-bar and brake at each change 5 in direction of wheel rotation, and by such change of rotation, substantially as described.

In testimony that I claim the foregoing as

my invention I have signed my name, in presence of two witnesses, this 13th day of December, 1882.

W. B. TURNER.

Witnesses:

JACOB J. STORER,

ALBERT P. MORIARTY.
